UNITED STATES PATENT OFFICE.

CHARLES E. SARGENT AND ROY B. PEEBLES, OF CHICAGO, ILLINOIS, ASSIGNORS TO CHICAGO CARD CUTTING COMPANY, OF CHICAGO, ILLINOIS, A CORPORATION OF ILLINOIS.

MACHINE FOR FEEDING BLANKS OR SHEETS TO PRESSES OR OTHER OPERATING DEVICES.

No. 927,171.

Specification of Letters Patent.

Patented July 6, 1909.

Application filed October 10, 1907. Serial No. 396,762.

To all whom it may concern:

Be it known that we, CHARLES E. SARGENT and ROY B. PEEBLES, citizens of the United States, residents of Chicago, in the county of Cook and State of Illinois, have invented certain new and useful Improvements in Machines for Feeding Blanks or Sheets to Presses or other Operating Devices, of which the following is a full, clear, and exact description.

This invention relates to improvements in machines for feeding blanks or sheets to presses or other operating devices and designs to provide a simple, practical and highly efficient machine for feeding blanks, one at the time, to a press or other device which is to operate upon the blanks.

The object of this invention is to avoid certain objectionable features in devices of this character, and to provide a machine which shall possess certain novel characteristics and advantages, a description of which will be found in this specification and the essential features of which will be more definitely pointed out in the claims.

The invention is clearly illustrated in drawings furnished herewith in which—

Figure 1 is a side elevation of a machine containing our improvements, and showing the same in connection with a diepress that is arranged to blank out cards from a blank strip. Fig. 2 is a diagrammatic view of certain operating devices and an electric circuit for operating said devices. Fig. 3 is a plan view of a blank. Fig. 4 is a plan view of the device. Fig. 5 is a vertical section taken on line 5—5 Fig. 4. Fig. 6 is an end view of the parts seen in Fig. 5 certain portions being cut away on the line 6—6 Fig. 5. Fig. 7 is a vertical section taken on line 7—7 Fig. 4. Fig. 8 is a detail vertical section taken on line 8—8 Fig. 6. Fig. 9 is a rear view of the parts seen in Fig. 8. Fig. 10 is a cross section taken on line 10—10 Fig. 4. Fig. 11 is a detail side view of a certain pressure regulating device. Fig. 12 is a detail rear view of a follower device. Fig. 13 is a detail, horizontal section taken on line 13—13 Fig. 1. Fig. 14 is a detail side view of a certain stop mechanism. Fig. 15 is a detail cross section taken on line 15—15 Fig. 14. Fig. 16 is a perspective view of a stop lever, and Fig. 17 is a rear view of a fragment of the follower device.

In general, the machine comprises a blank or strip holder 10, which is constructed and arranged to receive and hold a large number of the blanks or strips that are to be operated upon and in the preferred form of structure, this holder is so arranged that the strips may all stand upon end. The holder contains a suitably operated feed device 11, which is arranged to feed the blanks one at the time up and away from the remainder of the blanks.

A gate 12 is arranged in the path of the blank and is constructed to prevent the passage therethrough, of more than one blank at the time and said gate is operated and timed by suitable mechanism whereby the strips may follow each other in rapid succession. Above the gate 12 is located a horizontally extending feed device 13, which is arranged to feed the blanks on to the press 14. A second timing mechanism 15 is provided in connection with the feeding device 13, which is arranged to hold back an oncoming blank until the one preceding it has passed through the timer, thereby allowing only one blank at the time to be operated upon by the press. Mechanism is also provided for operating all of said parts so that they will operate together to feed the blanks from the stack one at the time to the press.

We will now proceed to describe the several parts in detail.

16—16 (see Figs. 5 and 6), are standards secured to the floor by angle brackets 17, and to a platform 18, by angle brackets 19. The other end of the platform is supported upon the body of the press 14, by angle brackets 20. The platform and standards afford a frame work for the operating parts. A pair of pulleys 21, 22, are journaled in bearings 23 23^a, upon said standards and carry a friction belt 24, against which the stock of blanks or strips are pressed by a follower, hereafterward described. The bearings of the pulley 22, are adjustably mounted upon the standards, whereby any slack in the belt may be taken up whenever it is found necessary. As shown the bearings 23^a, are mounted upon plates 25, which are slidably mounted in guide grooves formed between the standards 16, and guide strips 26. A cross-bar 27, connects the upper ends of the bearing plates 25, which bar is pressed downward by springs 28, that engage adjustment screws 29, which are threaded in a stationary

cross-bar 30, secured upon the standards. Turning the screws 29 in the proper direction will tighten up the belt.

Supplemental feed rollers 31, are journaled in brackets 32, mounted upon the slideable plates 25 and motion is given said rollers through a belt 33 and pulleys 34, 35. The rollers 31 are employed wherever extra long blanks or strips are to be handled. A plurality of backing pulleys 36, 37 are mounted between the two halves of the belt 24, the pulleys 36 being journaled in bearings upon the standards, and the pulley 37 being journaled in arms 38 adjustably secured upon the standards. As shown the arms 38 are pivotally connected to the standards so that by tilting said arms the pulley 37 may be swung toward or away from the stack of blanks. The purpose of this adjustment is to afford a close contact between the friction belt 24 and the strips, as it frequently happens that they are somewhat warped or bowed, in which case the roller can be adjusted to accommodate the belt to the strips.

The blanks are supported in position to be operated upon by a frame like device, comprising a bar 39 supported upon standards 40, 41, arms 42 and a follower device 43. The standard 41, is vertically adjustable, and is held in place by a clamp 44, secured upon the floor. By this arrangement the bar 39, can be given such an inclination as will facilitate movement of the blanks, toward the feed belt. The arms 42, hold the blank in place against the lateral movement and are adjustably mounted upon the standards by clamps 45. The follower 43, (see Fig. 12) comprises a bar 46, a plurality of fingers 47, pivoted to said bar, a shifting bar 48, pivotally connected to the fingers at points eccentric with respect to the pivotal connection between the fingers and bar 46, a supporting rod 49 pivotally connected with the bar 46, and with the platform 18. The pivot pin of the finger 47 has secured to it a lever 50 which may be turned to swing the fingers into operative position to engage the blanks, or swing them behind the bar 46. The bar 48, being connected to all of the fingers, causes them to swing in unison. A plurality of hooks 51, are fastened upon the bar 46 and a weight 52, is connected to certain of said hooks by ropes 53, 54 and pulleys 55, 56. This arrangement furnishes a follower device which holds the stack of blanks firmly in contact with the friction belt 24. Above the belt 24, is the timer or gate device 12.

Referring to Figs. 7, 8, 9 and 11, 57 and 58 are two plates which furnish a restricted passage way between them through which each blank must pass in its travel from the holder 10 to the feeding device 13. The plate 57 is stationarily supported by a bar 59, which is secured to the standards 16, and the plate 58 is adjustably supported upon a

bar 60 which is also secured upon the standards 16. A set screw 61, is threaded in a bar 62, which is supported upon the bar 60, and said screw bears upon the plate 58. By turning the screw 61 in the proper direction, the space between the two plates can be varied to conform to the thickness of the strips or blanks which are to pass through. In setting the plate 58 the screw 61 is turned in the proper direction until the width of the slit between the plates is approximately equal to the thickness of one blank or strip. The plate 58 has a flanged end 63, which guides the adjacent blanks toward the slit. A movable timing stop 64, normally obstructs the upper end of the passage way between the plate 57, 58, and said stop is carried by an arm 65, pivoted as at 66 to the bar 62, a spring 67 acting to draw the stop down upon the plates. The stop is positively held down during a portion of the time by means of a trigger or hook 68, pivoted to the bar 59 as at 69, which trigger is actuated by mechanism controlled by the passage of the blanks through the feeding device 13, and this mechanism is so timed that the trigger will release the stop only when a preceding blank has reached a predetermined position upon said feeding device, thereby avoiding the danger of piling the blanks upon each other in said feeding device. To obtain an instantaneous and effective operation of the trigger we have arranged a simple, electrically operated device, for this purpose, which as shown comprises a magnet 70, an armature 71, and a circuit closing device comprising two bars 72, 77 and a contact device 73, which circuit closing device is interposed in the circuit from the terminals of the magnet 70 to the generator. The armature 71 is arranged to depress the end of the trigger 68, whenever the magnet is energized, thereby swinging the trigger upon its pivot and releasing the stop 64, permitting the strip or blank to raise the stop, through the action of the friction belt 24, and to pass through the gate. The trigger 68 is returned to position for engagement with the stop 64, by a spring 74, which acts upon the trigger when the magnet is deenergized and returns it to its operative position. The end 75 of the trigger is beveled off so that whenever the stop 64 is swung down upon the plates, it will crowd the trigger back before it strikes the plates, whereupon the trigger will be returned by the spring 74 and engage the top of the stop.

The contact bar 72, is insulated from the remainder of the device by blocks 76, of insulating material, and is placed in such a position that the blanks or strips must necessarily pass over it, and the contact piece 73, is removably secured upon the bar 77. The bars 72, 77 act as terminals in the circuit and the contact piece 73 operates to open and close the circuit.

close the circuit between the terminals. The contact piece 73 comprises a clamp member 78, and a spring pressed contact finger 79. The clamp can be secured upon the bar 77 at 5 any point along its length, with the contact finger 79, in contact with the contact bar 72, and whenever the finger contacts with the bar 72 an electric circuit is established between the generator and magnet 70. When, 10 however, a blank or strip passes between the finger and bar the finger is raised by the blank and the circuit is broken. Thus the stop 64, is positively locked down by the trigger 68 except whenever no blank is 15 traveling between the circuit making and breaking device.

Adjacent to the gate 12, are journaled feed rollers 80, 84, 85 which engage the blanks and aid in advancing them through the gate. 20 Sprockets 81 and 82, mounted upon the shafts 80^a and 21^a of the roller 80 and pulley 21 respectively and a sprocket chain 83 afford means for revolving the roller 80. The rollers 84 are revolved by sprockets 86, 87, 25 and a chain 88. The rollers 85, are journaled in arms 89 which are supported upon the bar 60, and said rollers are held in frictional engagement with the rollers 84 by set screws 90, that are threaded in brackets 91 also secured 30 upon the bar 60. The rollers 84, 85 are located on the sides of the stop 64, and take hold of the blanks just as they emerge from the gate 12.

A guide strip 92, is secured to the platform 35 18, and is adapted to turn the blanks from a vertical position into a position to be acted upon by the feed devices 13. The platform is formed with an opening 93, at a point, immediately above the gate 12, through 40 which opening the blank passes from the gate 12 to the feed devices 13. The guide strips 92 bears a pressure roller 94, which bears upon the feed belt 95, that forms part of the feed device 13, and said roller 94, is 45 positioned immediately above a pulley 96, which carries one end of the belt 95. The guide strip 92 is preferably composed of spring material, and presses the roller 94, down upon the belt 95, so that whenever a 50 blank is fed in between said roller and belt, it will be carried on toward the press, after it leaves the rollers 84, 85.

The belt 95 is carried by the pulley 96 and by a drive pulley 11, which is located adjacent to the press and is belted to the press by a belt 98, which runs over pulleys 99 and 100, and an idler 101. The pulley 99 is mounted on the shaft which bears the pulley 97 and the pulley 100, is mounted on the shaft 100^a 60 of the press 14.

A friction roller 103, bears upon the belt 95, at a point immediately above the pulley 97, and said roller is pressed down upon the same by spring arms 104, the roller being 65 mounted upon a shaft 105, which is journaled

in the free ends of the arms 104. Guides 106 are provided for directing the blanks in between the dies of the press, and said guides may be of any well known form for guiding the blanks to the dies.

70

Adjacent to the rollers 103, is the timer 15, which arrests the movement of the blanks until the one preceding it has gone a certain distance beyond the roller 103, the object being to time the movement of the blanks so 75 that they will follow each other in rapid succession to the dies, and at the same time prevent more than one, at the time, from being operated upon by the dies. As shown the timer comprises a trigger 107, (see Figs. 80 4, 14, 15 and 16) pivoted upon a bracket 108 and having arms 109, 110 one of which is arranged to lie in the path of the blanks and to obstruct their movement except at certain predetermined times, and the other of which 85 is arranged to be engaged by an arm 111^a carried by the armature 111 of a magnet 112, for bringing the other arm 109, out of the path of the blanks. The circuit to said magnet is controlled by contact pieces 113, 114, 90 which form the terminals of the circuit. The contact piece 113, is located upon the reciprocating head of the press, and the contact piece 114 upon the frame of the device, and in position to contact with the contact piece 95 113 whenever the head reaches the bottom of its stroke. Hence every time that the contact pieces 113, 114, touch each other the magnet 112 is energized and the trigger operated to 100 release any blank which happens to be held back by the trigger. The contact piece 114, is however located below the plane of travel of the blanks so that they must necessarily pass between the contact pieces 113, 114, the result being that the magnet remains de- 105 energized whenever a sheet is passing between the contact pieces. Thus the trigger is held in operative position until the sheet has cleared the contact pieces whereupon contact will be made the next time that the 110 head comes down, the magnet will be energized and the trigger operated to release the sheet which it is holding back. Guides 115, 116 are provided to guide the blank against the arm 109 of the trigger and a roller 117 is 115 mounted just below the arm, over which roller the blank rides on its way to the press.

A belt guide 118, is placed under the upper bight of the belt 95, at a point adjacent to the guide 115, thereby bringing the belt into 120 alinement with said guide. This is for the purpose of directing the blanks against the trigger 107. The shaft 100^a of the press bears a pulley 120, which is connected with a pulley 122 upon the shaft 21^a of the feeding mechanism 11.

In operation the blanks are fed up by the feed belt, 24, the gate 12 permitting only one at the time to pass through it. There being no blank upon the feeding device 13, the 130

magnet 70 is energized and the stop is free to be raised by the blank. The blank is then pushed through the gate by the feeding devices 11 until it reaches the belt 95 and 5 roller 94 whereupon the belt takes hold and advances the blank to the trigger 107. While the blank is passing under the contact piece 73 the magnet 70 is deenergized and the stop 64, is locked down, but as soon as the blank 10 has passed beyond the contact piece, 73 the circuit is closed and the stop is unlocked, thereby permitting another blank to follow the preceding one. There being no blank 15 between the contact pieces 113, 114, the arm 109 is raised every time that the head of the press comes down, and as soon as the blank reaches the trigger it passes on and through the press. The contact piece 73 should be set at such position upon the bar 77 that the 20 blanks will follow each other in quick succession, and it is highly desirable to have a blank reach the trigger just about the time that the preceding one is leaving or has left the trigger. The arm 109 of the trigger rests 25 upon the blank while the latter is passing under the trigger, but the trigger immediately falls down into operative position as soon as the blank has passed by, thus preventing the following blank from reaching 30 the press before the preceding one has been fully acted upon.

Among the important advantages of this device is its capacity for feeding the sheets or blanks to the press the accuracy of the feed, 35 and the adjustability for various sizes of blanks. It requires practically no attention except to keep the holder stocked with blanks.

While only one form of construction has 40 been shown and described it is not to be understood that we desire to limit ourselves to the precise details shown and described. Furthermore the various parts may be used in them entirely or may be used separately.

45 We claim as new and desire to secure by Letters Patent:

1. Mechanism for holding a stack of blanks in position, mechanism for feeding the blanks out of said stack, one at a time, a movable 50 stop, means for yieldingly holding said stop in the path of the blanks, mechanism for positively locking said stop in operative position or releasing it therefrom, and timing mechanism controlled by the passage of blanks therethrough, for operating said stop locking and releasing mechanism.

2. Mechanism for holding a stack of blanks in position, mechanism for feeding the blanks out of said stack, a gate arranged to permit 60 one blank at a time to leave the stack, a spring pressed stop for closing the gate, said stop being adapted to be moved out of such closed position by an outwardly moving blank, stop locking and releasing mechanism, 65 and timing mechanism controlled by the pas-

sage of blanks therethrough, operating to actuate said stop locking and releasing mechanism to control the advancement of each blank.

3. Mechanism for holding a stack of blanks 70 in vertical position, mechanism for feeding the blanks out of said stack, an adjustable gate arranged to permit one blank at a time to leave the stack, a stop, means for yieldingly holding said stop in the path of the 75 blanks, stop locking and releasing mechanism, and timing mechanism controlled by the passage of blanks therethrough operating to actuate said stop locking and releasing mechanism to regulate the advancement of each 80 blank.

4. A stack holder, mechanism for feeding the blanks out of the stack one at a time, a spring pressed stop adapted to be forced out of the path of a blank by the forward move- 85 ment of the blank, a stop locking and releasing mechanism containing a trigger, and timing mechanism controlled by the passage of a blank therethrough for operating the trigger to release the stop. 90

5. In a device of the class described, the combination of a stack holder, a constantly moving feed mechanism, a follower for holding the stack in constant contact with the feed mechanism, a gate, a spring pressed 95 stop for the blanks adapted to be lifted out of the way by the outgoing blank, stop locking and releasing mechanism, and a suitably operated timing mechanism controlled by the passage of blanks therethrough, arranged 100 to operate said stop locking and releasing mechanism.

6. In a device of the class described, the combination of a stack holder, a constantly moving feed mechanism, a follower for holding the stack in constant contact with the feeding mechanism, a regulatable gate, a spring pressed stop for the blanks adapted to be lifted out of the way by an outgoing 105 blank, stop locking and releasing mechanism, and a suitably operated timing mechanism 110 arranged to operate said stop locking and releasing mechanism.

7. Mechanism for lifting long blanks out of a vertically extending stack of blanks, 115 comprising two pulleys, one of which is journaled adjacent to the top of the stack and the other of which is journaled adjacent to the bottom of the stack, means for revolving the upper pulley, a friction feed belt 120 extending around the pulleys and having one bight lying parallel with the blanks and in continuous contact with the end blank of the stack, an idler intermediate said pulleys bearing upon said bight of the belt and 125 means for adjusting said idler toward the stack to deflect said bight of the belt out of its normal path and thereby force it into contact with the blank at all points along its 130 length.

8. Mechanism for lifting blanks out of a vertically extending stack of blanks, comprising two pulleys, one of which is journaled adjacent to the top of the stack and the other 5 of which is journaled adjacent to the bottom of the stack, means for revolving the upper pulley, a friction feed belt extending around said pulleys and having one bight lying parallel with the blanks and in continuous contact with the end blank of the stack, an idler bearing upon said bight of the belt, means for adjusting said idler toward the stack to deflect said bight of the belt out of its normal path and thereby force it into contact with 10 the blank at all points along its length, and a follower bearing upon said stack.

9. Mechanism for feeding long blanks out of a vertically extending stack of blanks, comprising a friction feed belt having one 20 bight lying parallel with the blanks and in continuous contact with the end blank of the stack, an adjustably mounted idler, bearing upon said bight of the belt and adapted to be adjusted toward said stack to deflect said 25 bight of the belt out of its normal path and thereby force it into contact with the blank at all points along its length, a follower bearing upon said stack, a gate and a suitably operated stop for permitting one blank at a 30 time to leave the stack.

10. Feed mechanism, a gate, a stop for the blanks, a spring for yieldingly holding said stop down, a trigger operating to positively hold said stop in operative position, a magnet for actuating said trigger and a circuit closing mechanism actuated by the passage of the blanks through said circuit closing mechanism.

11. A feed belt, friction feed rollers, a gate 40 adjacent to said rollers, a stop therein, a spring for yieldingly holding said stop down, a trigger operating to positively hold said stop in operative position, a magnet for actuating said trigger and a circuit closing 45 mechanism actuated by the passage of the blanks through said circuit closing mechanism.

12. In a device of the class described a blank arresting mechanism comprising a 50 guide for the blanks, a stop for the blank, a trigger for positively holding the stop in locked position and an electrically controlled timing mechanism for actuating said trigger.

13. Feeding mechanism, a gate, a stop for 55 the blanks, mechanism operating to release said stop comprising an electric magnet, a contact bar forming one terminal of the magnet circuit and a contact piece forming the other terminal of the circuit mounted so 60 as to be longitudinally adjustable with respect to said contact bar, said contact piece being arranged to make contact with the bar, and a conveyer arranged to convey the blanks between said contact pieces.

14. In a device of the class described, a

blank arresting mechanism, comprising a stop, a magnet operating to release said stop, a contact bar forming one terminal of the magnet circuit, and a contact piece forming the other terminal of the circuit, said contact piece being mounted so as to be longitudinally adjustable with respect to said bar, and means for operating said contact piece to make and break the circuit. 70

15. In a device of the class described a blank arresting mechanism, comprising a stop, a magnet operating to release said stop, a contact bar forming one terminal of the magnet circuit, and a contact piece forming the other terminal of the circuit, said contact piece being mounted so as to be longitudinally adjustable with respect to said bar, and a conveyer arranged to convey the blanks between said contact devices. 80

16. In a device of the class described the combination of a stop for arresting the movement of the blanks, a magnet operating to release said stop, a conveyer, a pair of contact bars extending longitudinally of said conveyer, and forming the terminals of the magnet circuit, and a contact piece adjustably mounted upon one of said bars, and adapted to be actuated by the blanks to make and break the circuit. 85

17. In a device of the class described the combination of a stop for arresting the movement of the blanks, a magnet operating to release said stop, a conveyer, a pair of contact bars extending longitudinally of said conveyer, and forming the terminals of the magnet circuit, and a contact piece adjustably mounted upon one of said bars, and having a spring actuated contact finger contacting with the other bar, and arranged to be raised out of contact by the blanks while passing by said contact piece. 95

18. Mechanism for segregating blanks and advancing said blanks one at a time, a device for operating upon said blanks, a circuit closer having a stationary contact piece, and a movable contact piece carried by a moving element of the operating device, and stop mechanism having a magnet in the circuit of the circuit closer and arranged to arrest the movement of the blanks immediately in front of said operating device. 110

19. Mechanism for segregating blanks and advancing said blanks one at the time, a device for operating upon the blanks a stop mechanism arranged to arrest the movement of the blanks, a magnet for actuating the stop, terminals for the magnet circuit, one of which is carried by the device which operates upon the blanks, for intermittently closing the circuit. 115

20. The combination of a blank conveyer, a trigger for arresting the movement of the blanks, a magnet operating to move said trigger out of the path of the blanks, a device for operating upon blanks and a circuit 120 125 130

closer having two terminals, one of which is carried by a moving element of the device for operating upon the blanks and is carried across the path of travel of the blanks through said operating device.

21. The combination of a blank conveyer, an arresting trigger, a magnet for operating said trigger to release a blank which is arrested thereby, a device for operating upon the blanks, a circuit closer having a movable member carried by a moving element of the operating device, and guides adapted to direct the blanks between the members of said circuit closer.

15 22. The combination of a segregating device comprising a friction feed belt, a gate, a stop, and stop locking and releasing mechanism, a device for operating on the blanks, a friction feed belt for feeding the segregated blanks to the operating device and a circuit making and breaking device carried by the

operating device, and between which the blanks are caused to travel, one member of which is carried by a moving element of the operating device.

25

23. In a device of the class described the combination with a feed mechanism of a follower comprising a bar, a plurality of fingers, pivoted thereto and a connecting bar arranged to swing said fingers, in unison, into 30 and out of operative position.

In witness whereof we have executed the above application for Letters Patent of the United States this 4th day of October 1907, at Chicago, county of Cook and State of Illinois.
